UNITED STATES PATENT OFFICE

MERL R. WOLFARD, OF CAMBRIDGE, MASSACHUSETTS, ASSIGNOR TO CHARLES F. HOPEWELL AND HELEN C. HOPEWELL, A COPARTNERSHIP DOING BUSINESS AS HOPEWELL BROTHERS, OF WATERTOWN, MASSACHUSETTS

CARBURETOR

Application filed July 17, 1928. Serial No. 293,371.

This invention relates to improvements in carburetors and provides a simple design for effectively proportioning the mixtures at all times through unit-controlling means with 5 means for temporarily enriching the mixture for starting, together with inherent temperature and barometric regulation whenever necessary, and further eliminates the necessity of accessory acceleration devices.

10 A principal object thereof is to provide a simple design of mixture-proportioning parts so positioned and correlated that a single or unit control will produce a substantially proportional change in the fuel-air ratio 15 during idle and light load operation as well as under heavier load operation.

In the operation of an internal combustion engine a rich fuel-air mixture is required at cold starting and as the engine warms up 20 the ratio of fuel to air must be decreased for economical and satisfactory operation until normal operating temperatures are reached.

Also during normal operation at low atmospheric temperature the ratio of fuel to 25 air must be greater than at high atmospheric temperatures.

Furthermore, while operating at any temperature the ratio of fuel to air should be gradually increased below about half load as 30 the load decreases to idle operation of the engine. In order to produce this last result a plurality of passages for the fuel or for the fuel-air mixture have been employed in previous carburetor constructions, but have 35 been so related to each other as to cause an interruption or reversal of flow through certain of said passages as the operating load changes, thus causing a temporary storage of a portion of the fuel. This results in a 40 leaning down of the mixture in proportion to the amount of storage and requires an over-enriching of the mixture, to compensate for the lag in flow, in order to secure proper operation of the engine.

45 Therefore, no single or unit control has been, or can be, employed in such carburetor constructions as is required to satisfy the two previously stated conditions, namely, to produce a proportional change in the fuel- 50 air ratio throughout the entire operating

range from idle to full load either during cold starting and warming up of the engine, or during changes in atmospheric temperature.

An object of the present invention is to 55 provide means for producing a proper proportioning of the fuel-air mixture in combination with means effecting uninterrupted mixture flow from the fuel inlet and there- 60 beyond under all normal conditions of operation from idle to full load.

The term "uninterrupted mixture flow" as used herein signifies a continuous carrying forward of the fuel in the air from the fuel inlet without cessation or diminution and 65 avoiding a lag in the flow of any considerable portion of the fuel from the fuel inlet and therebeyond, such as would be caused by a temporary storage or reversal of flow of 70 any portion of the fuel between the fuel inlet and the carburetor outlet. Thus uninterrupted mixture flow insures continuously an undiminished flow of fuel through the carburetor and avoids the necessity of over- 75 enriching the mixture to compensate for any reduction in the fuel delivered to the carburetor outlet caused by the storage or the reversal of flow of fuel.

This is accomplished in a preferred embodiment of the invention by placing the 80 fuel-inlet in the air metering section of the mixing passage and providing means maintaining a low, predetermined flow of fuel through the fuel inlet irrespective of the suction head in the air metering section, in combination with the positioning of the throttle valve so as to maintain uninterrupted mixture flow beyond the fuel inlet. 85

A further object of the invention is to provide unit-controlling means operable to vary 90 the relative proportion of fuel to air supplied to the mixing passage.

Another object of the invention is to provide means for entraining the fuel in the air in such a positive and definite manner as to 95 eliminate the necessity of providing special means for supplying additional fuel during the acceleration of the engine, such as accelerating wells, fuel pumps, etc.

Another object of the invention is to pro- 100

vide thermostatic mechanism operable to actuate the unit-controlling means in such a manner as to regulate the fuel-air ratio, that is, the ratio of fuel to air, under all conditions of operation, with a degree of precision heretofore unattained.

A further object of the invention is to provide barometric mechanism operable, preferably in conjunction with the thermostatic mechanism, still further to refine the precision of the fuel-air ratio, thereby adapting the carburetor for use in varying altitudes.

Another object of the invention is to provide means for continuously supplying fuel at a low, predetermined head to the fuel inlet, preferably located in the air metering section, to supplement the rate of flow induced by the suction head in the air metering section acting upon the fuel inlet during normal operation of the engine from idle to about half load, in combination with a throttling valve in the mixing passage having its lower end portion below and beyond said fuel inlet operable to maintain an uninterrupted mixture flow from the metering section to the engine during idle and light load operation.

A further object of the invention is to provide a depression in the mixing passage beyond and below and in proximity to said fuel inlet to receive fuel which may flow by gravity from said inlet and a throttling valve having its lower portion extending into said depression operable during idle and light load operation to maintain an uninterrupted mixture flow.

A further object of the invention is to position the throttling valve in such proximity to the metering section that when approaching wide open position a segment of said throttling valve will project into the metering section to restrict its effective area, thereby increasing the ratio of fuel to air.

A further object of the invention is to provide a fuel reservoir surrounding said fuel inlet having means for maintaining a liquid level in said reservoir slightly above said fuel inlet, with the wall of said mixing passage extending above the liquid level in said reservoir adapted to prevent loss of fuel when the engine is not in operation.

Another object of the invention is to provide a reservoir surrounding the fuel inlet and communicating therewith having means for supplying fuel to said fuel reservoir including a regulating valve and float sections in said reservoir symmetrically positioned relatively to said fuel inlet, with lever mechanism intermediate of said float sections and said regulating valve operable to transmit a sufficiently large and substantially constant multiplied force to said regulating valve irrespective of the inclination of said reservoir, whereby the fuel in the reservoir will be maintained with only small variations in height above or below a predetermined level

during idle and light load operation of the engine.

These and other objects and features of the invention will more fully appear from the following description and the accompanying drawings, and will be particularly pointed out in the claims.

Illustrative embodiments of the invention are shown in the accompanying drawings, in which,

Fig. 1 is a view mainly in vertical longitudinal section of a preferred embodiment of the invention in which the fuel level is maintained slightly above the fuel inlet to the mixing passage to produce a continuous flowing head;

Fig. 2 is a plan view of the same;

Fig. 3 is a detail view illustrating the connection between the fuel valve and the thermostatic device for controlling the same;

Fig. 4 is a view, partly in end elevation and partly in vertical section, showing particularly the mechanism for regulating the level of liquid in the reservoir;

Fig. 5 is a detail view, mainly in vertical section, illustrating a modified form of the invention comprising an automatic throttling valve for maintaining uninterrupted flow of mixture during idle and light load operation with a usual type of throttle valve;

Fig. 6 is a detail view illustrating a modified arrangement of fuel inlet and valve;

Fig. 7 is a view, mainly in vertical section, illustrating another embodiment of the invention in which a continuous flowing head is produced in a different manner;

Fig. 8 is a horizontal sectional view of a portion of the construction illustrated in Fig. 7, on line 8—8, Fig. 7;

Fig. 9 is a detail plan view of means for locking the fuel valve cage in adjusted position;

Fig. 10 is a graphic illustration showing curves based respectively upon the load percentage and fuel-air ratio and illustrating a comparison between the action of the usual suction head and a flowing head, and the advantages attained by the flowing head of the present invention; and

Fig. 11 is a graphic illustration showing curves based respectively upon the load percentage and fuel-air ratio and illustrating the manner in which the present invention maintains a mixture ratio within the desired ranges both of maximum efficiency and maximum power.

The carburetor illustrated in Figs. 1 to 4 of the drawings comprises a casing 1 having a mixing passage consisting of an inlet section 2 and an outlet section 3, preferably relatively inclined to each other, forming at their junction a depression 4. The mixing passage is so formed as to provide a restricted portion of an air metering section 5 of reduced area within the inlet section and pref-

erably in front of and in proximity to the depression 4. Such air metering section of restricted area may be provided in any suitable manner. In the construction illustrated herein a filler 6 is secured to, or formed integral with, the upper portion of the cylindrical wall of the casing and presents a flat lower face which in conjunction with the lower wall of the inlet section provides a substantially semi-cylindrical metering section of the desired restricted area. A fuel inlet 7 leads to the air metering section of the mixing passage. If the minimum area of the air metering section is at the fuel inlet, the quantity of air flowing past the fuel inlet relative to the suction head at the fuel inlet is determined by the area of the air metering section at the fuel inlet. If the minimum area is in front of and in proximity to, instead of exactly at the fuel inlet, the relative quantity of air flowing proportional to the suction head at the fuel inlet will still be effectively determined by the area of the air metering section.

25 Mechanism for maintaining the liquid at the proper height above the fuel inlet, as illustrated in the present invention, comprises a reservoir 8 having therein cylindrical float sections 9 and 10 symmetrically positioned relatively to the fuel inlet, with lever mechanism intermediate of the float section and valve operable to transmit a sufficiently large and substantially constant multiplied force to the regulating valve regardless of the inclination of the reservoir thereby to maintain with a proper degree of precision in the height of the fuel level during idle and light load operation.

In the particular construction illustrated 40 the lever mechanism comprises a yoke 11, the arms 12 of which extend to the lower portion of and are attached to the float sections 9 and 10, while the body of the yoke extends substantially horizontally and is pivotally mounted at its end upon a pin 13 carried by lugs 14 extending downwardly from the casing 1.

A lever 15, having at one end a knife edge 16, engages the yoke 11 and at its opposite end is pivotally mounted upon a pin 17 carried by lugs 18 depending from the casing 1.

The casing 1 is provided at one side of the passage 3 with an upwardly extending boss 19 bored vertically to provide a fuel supply passage 20 leading to the reservoir. The upper portion of the wall of the bore is screw threaded to receive the complementary screw threads of a valve cage 21 which desirably has an angular or hexagonal enlargement 22 at a distance from its upper end. The upper end of the portion of the valve cage is provided with external screw threads 23 to receive a coupling 24 for the end of a supply pipe 25.

25 A valve seat member 26 is interposed be-

tween the coupling 24 and the upper end of the valve cage 23 and comprises a head which rests upon the upper end of the cage and a downwardly extending cylindrical portion 27 which desirably is pressed into the upper end of a vertical cylindrical passage 28 of the valve cage. The valve member has a vertical central bore 29, the lower end of the wall of which is tapered to form a conical seat complementary to the conical end of a regulating valve 30 which extends axially of the passage 20 in the boss and of the passage 28 of the valve cage. The lower end of the valve 30 is provided with a reduced extension 31 which passes through a suitable aperture in the lever 15 located in proximity to the pivot 17 of said lever and the shoulder 32 at the base of the extension 31 desirably is slightly rounded and so constructed that it contacts with the lever 15 slightly below the pivot 17 of the lever when the regulating valve is normally closed.

By reason of this construction no sliding contacts are present which would interfere with the free movement of the valve. Furthermore, the vertical swinging movement of the lever 15, even though slight, transmits a sufficient lateral movement to the lower end of the valve 30 which will prevent the sticking of the valve upon its seat.

As the distance between the fulcrum of the lever 15 and the point of engagement therewith by the valve 30 is very much shorter than the distance from such point of engagement to the knife edge 16 at the end of the lever which engages the yoke, and as the distance between the point of engagement of the knife edge 16 is much closer to the pivotal support 13 of the yoke than the distance from the knife edge to the center of the float sections, a very substantial multiplying leverage is interposed between the float sections and the regulating valve which insures delicate regulation of the height of the fuel level in the reservoir during idle and light load operation of the engine. This multiplied leverage necessitates a substantial drop in the position of the float sections, (about $3\frac{1}{8}$ ") when the engine is operating at full load in order to permit a sufficient amount of fuel to flow into the reservoir.

By reason of the adjustability of the valve cage 21 within the boss 19, the vertical position of the valve seat may be varied to establish the liquid level in the reservoir at a predetermined height above the fuel inlet.

Positive locking means desirably are provided to retain the valve cage in adjusted position. Any suitable means may be employed. In the present construction a locking plate 33 is provided which has an aperture therethrough having walls complementary to the walls of the hexagonal head and extends laterally therefrom over the upper end 34 of the boss and rests thereupon.

The extension 33 desirably is provided with a plurality of apertures 35 and 36 to receive a screw 37 adapted to be seated in a suitable socket in the upper end 34 of the boss.

An important feature of the invention as illustrated in Figs. 1 to 4 inclusive consists in providing means located beyond and in proximity to the fuel inlet operable to maintain an uninterrupted mixture flow during idle and light load operation as well as under heavier load. This is accomplished by providing a throttling valve 39 in the outlet section which is in the general form of a butterfly valve, secured by suitable screws to the flattened portion of a shaft 40 which extends transversely of the outlet passage and is rotatably mounted in the walls of the casing. The shaft 40 may be provided with a suitable arm 41 adapted to be connected to the usual throttle control upon the instrument board.

The upper end portion 42 of the valve 39 desirably is substantially flat and when in closed position, as illustrated in Fig. 1, completely closes the upper portion of the outlet passage. The lower end portion 43 of the valve 39 desirably is made somewhat thicker than the upper portion and is curved toward approximate parallelism with the lower wall of the outlet passage and when the valve is closed is spaced slightly therefrom and extends into the depression 4 which, as illustrated in Fig. 1, is at the junction of the relatively inclined inlet and outlet sections of the mixing passage.

The space 44 between the lower end of the valve 43 and the wall of the outlet passage is such as to permit the passage of only sufficient fuel-air mixture to cause the engine to operate satisfactorily on idle, and the passage between the lower end portion of the valve and the casing increases gradually from the lower end of the valve for a short distance therebeyond in order to reduce the swish produced by the very high velocity and effective breaking-up of the fuel which is drawn through this passage by the suction of the engine when running at light load.

By reason of the fact that fuel is delivered through the fuel inlet under a low flowing head maintained irrespective of the suction head in the metering section of the mixing passage, the suction head in the mixing passage, acting upon the fuel inlet, in addition to this low flowing head, will produce a properly proportioned mixture during idle and normal operation of the engine up to and somewhat beyond half load. This properly proportioned mixture flows uninterruptedly, (without requiring additional energy from the air stream to lift the fuel,) into the depression 4, and the throttling valve, which projects into the depression 4, maintains uninterrupted mixture flow during idle and light load operation, as well as during heavier loads.

The throttling valve 39 desirably is so positioned that when it is moved toward wide open position the lower end will intersect the plane of the air metering section 5 as the throttling valve moves from beyond half open toward full open position. As the throttling valve moves from beyond half open position toward full open position, the lower portion of the valve swings into the air metering section of the mixing passage in such a manner that the thickened lower end portion of the valve reduces that area of the air metering section which is above the fuel inlet and normal to the inclination of the inlet section. This reduction of the area of the air metering section increases the suction head at the fuel inlet and consequently increases the ratio of fuel to air as wide open throttle is approached where maximum power is the prime consideration.

While the mixture thus obtained may be richer than that required for maximum efficiency, it is desirable that such mixture shall be supplied to produce maximum power as the throttle approaches full open position which is only required during a comparatively short time relatively to the total time during the normal operation of automobile engines.

A preferred mechanism for changing the fuel-air ratio over the entire range of load from idle to full load of the engine, which is illustrated in Figs. 1 to 4 inclusive, comprises a valve 45, preferably of cylindrical form, which extends across the metering section and is slidably mounted in the fuel inlet 6 with the cylindrical up-stream wall 46 complementary to the cylindrical up-stream wall of the inlet port. The lower portion of the valve is chamfered or cut-away upon the down-stream side preferably to present a flat face 47 cut at an acute angle to the axis of the valve, so that by raising and lowering the valve the effective area of the outlet will be increased or decreased.

In usual carburetor constructions of this type, in which a needle valve is employed, the needle valve is guided in the wall of the mixing passage opposite to the fuel inlet and is provided with a screw threaded adjustment. Where the guide for the needle valve is so remote from the fuel inlet relative to the distance between the valve and the wall of the inlet, rotative adjustment is likely to bring the valve into contact, or in closer proximity to the wall of the inlet nearer to the up-stream side than to the down-stream side, or vice versa thereby permitting a considerable variation in the amount of fuel delivered from such fuel orifice.

A further object of the invention is to eliminate such variation by providing means for maintaining a wall of the valve in light, but positive engagement with the complementary wall of the inlet, thereby avoiding erratic

changes in the fuel-air ratio with small adjustments in the position of the valve.

In the construction illustrated in Figs. 1 to 4 inclusive, the up-stream wall of the valve 6 is maintained in contact with the complementary wall of the inlet section by an inclined strut acting upon the thermostat which regulates the position of the valve in response to variations in temperature in the mixing 10 passage.

The cylindrical section of the needle valve, which crosses the mixing passage, merges into a stem of considerably larger diameter, the lower portions of the lower end of the stem 15 being cut away to present parallel flat surfaces 48 and 49, with a registering notch 50 upon the down-stream side which presents a shoulder 51 adapted to be engaged by a thermostatic controlling member.

The preferred form of thermostat shown in Fig. 1 comprises a strip of preferably bimetallic thermo-sensitive metal in the form of a return bend and having an approximately horizontal portion 52 provided at its end with a rectangular slot 53, (see Fig. 3), adapted to be slipped over the valve and cut-away portions 48 and to engage the shoulder 51 within the notch 50. The engagement of the sides of the slot 53 with the walls 48 and 49 of the valve stem prevents 20 rotative movement of the valve.

The thermostatic strip at the opposite end of the arm 52 is bent at a substantially right angle to present a vertical section 54 which 25 in turn is bent to present another right angle turn 55 and is bent downwardly therefrom toward the arm 52 to permit it to be conveniently assembled within the mixing passage with the end 56 of the arm desirably 30 extending horizontally in substantial parallelism with the arm 52. The thermostatic member is pivotally supported within the right angle bend 55 by a strut 57 which is pivotally mounted at its lower end upon a 35 pin 58 and extends upwardly and at an inclination away from the vertical axis of the valve and engages the thermostatic member within the right angle bend 55.

The end 56 of the thermostatic element is 40 adjustable by means of a rod 59 which is reciprocably mounted in the upper wall of the casing 1 and at its upper end is engaged by or attached to a device 60, such as a sylphon bellows, responsive to changes in barometric pressure, the upper end of which is 45 engaged by an adjusting screw 61 which is adjustably mounted in the arm 62 of a bracket 63 which is secured by suitable machine screws 64 to the casing 1.

Elastic means desirably are provided for 50 forcing the valve upwardly to maintain the shoulder 51 of the valve stem in contact with the under face of the arm 52 of the thermostatic member. As illustrated in Fig. 1 this 55 is accomplished by a spiral spring 65 which

rests upon a shoulder of the casing 1 and engages at its upper end a pin 66 extending transversely through the upper end of the valve stem.

Manual means may be provided for temporarily opening the valve during cold starting of the engine. Such means may be in the form of a bell crank 67 which is pivotally mounted upon a pin 68 carried by bosses 69 extending upwardly from the casing 1 and 70 having one arm 70 extending beneath the pin 66, with the other arm 71 of said bell crank connected by a cable or rod 72 with suitable hand operated means conveniently located upon the instrument board of the automobile, (not shown).

A light engagement of the needle valve with the complementary wall of the fuel inlet is maintained by the pivotally mounted strut 57 which inclines away from the vertical axis of the valve and engages within the right angle bend 55 of the thermostat, thus holding the end wall of the slot 53 against the base of the notch 50 in the valve stem and exerting a gentle pressure tending to hold the up-stream wall of the valve in contact with the complementary wall of the inlet and also holds the valve in contact with an upper bearing in the casing.

The position of the valve 46 may be initially adjusted by actuation of the screw 61 which, acting through the end 56 of the return bend of the thermostat, serves to force the arm 52 downwardly against the tension of the spring 65.

In the operation of the device upon cold starting the operator by pulling upon the cable or rod 72 will rock the bell crank 67 and thereby raise the valve 46 against the elasticity of the thermostatic element sufficiently to provide an additional fuel supply during the cold starting of the engine. By reason of the fact that the thermostat is formed as a return bend and composed of two substantially right angle bends, an increased flexure is attained as the flexure at each right angle bend is substantially equal to that which would be attained if the thermostat were merely bent into U-shape.

A modified construction is illustrated in Fig. 5 in which the mixing passage comprises relatively inclined inlet and outlet sections 2 and 3 with a depression 4 at the junction of said sections and having a metering passage 5 and filler 6, a fuel inlet 7 and a fuel valve 46 as herein described, but which differs from the construction illustrated in Figs. 1 to 4, in which an automatic throttling valve 73 is provided to maintain an uninterrupted mixture flow during idle and light load operation, with the usual manually operable throttle valve 74 which controls the quantity of mixture flow to the engine. The throttle valve 74 desirably is of the butterfly type and is secured to a shaft 75 extend-

ing transversely of the outlet passage in the central plane thereof, and is provided with a suitable actuating lever 76 adapted to be connected by suitable means to the instrument board.

The automatic throttling valve 73 is mounted upon a shaft 77 which extends transversely of the mixing passage and is pivotally mounted in the walls thereof sufficiently below the axis thereof to present a larger area above the pivot which is subjected to the suction of the engine than that which lies below the pivot. The lower portion 78 of the automatic throttling valve is of sufficiently greater thickness, or is so weighted, as to tend to maintain the valve in closed position.

The relative weight of the lower portion of the valve should be such as to maintain the valve practically in its closed position until a suction head of predetermined value is reached. Experiments have shown that a suction head of eight to twelve inches of water will be sufficient to give excellent atomization of fuel below the lower edge of the automatic throttling valve. The contour of the lower edge of the automatic throttling valve should be substantially as heretofore set forth with respect to the embodiment of the invention illustrated in Figs. 1 to 4 inclusive.

Another form of fuel inlet and regulating valve therefor adapted to avoid erratic flow of fuel from the fuel inlet, with changes in adjustment, is illustrated in Fig. 6, in which a conduit 79 is provided to communicate with the fuel reservoir, with a lateral aperture 80 therein which communicates with an inclined inlet passage 81 leading to the air metering section above and in proximity to the depression 4 at the junction of the inlet and outlet sections as heretofore described. In this construction the regulating valve is in the form of a needle valve 82 which slidably fits within the upper end portion of the conduit 79 with the tapered portion 83 of the valve extending across the aperture 80. The needle valve 82 desirably extends across the mixing passage and may be controlled by the mechanisms illustrated in Fig. 1. Inasmuch as the needle valve 82 is provided with a bearing 84 near the point of fuel control, it is practically free from lateral movement relative to the surrounding wall of the inlet and it is so positioned that the flow of fuel is unaffected by the current in the mixing passage.

Another embodiment of the invention as illustrated in Figs. 7, 8, and 9, comprises a casing 85 having an inlet section 86 and an outlet section 87 with an air metering section 88 therebetween of a predetermined fixed area. As illustrated an air metering section of reduced fixed area is formed by providing a filler 89 having a Venturi passage therethrough. In this construction the res-

ervoir having a wall 90 preferably symmetrically surrounds the fuel inlet and is mounted upon or is integral with the wall of the casing 85. In this construction the reservoir communicates through a small orifice 91 located near the bottom of the reservoir with a vertical inlet conduit 92 in a boss 93 the central portion of which extends upwardly a short distance above the fuel level which is maintained in the reservoir. The upper end of the passage 92 desirably is provided with a sleeve 94 forming a fuel inlet the area of which is controlled by a valve 95 which is slidably mounted in said fuel inlet. The peripheral wall 96 of the boss desirably is of oblong form, as illustrated in cross section in Fig. 8, and extends upwardly into engagement with the under face of the cover 97. A suction passage 98 extends upwardly from the inlet section, thence horizontally across the fuel inlet, and thence downwardly, and is so branched beyond that one branch 99 communicates with the outlet passage beyond the throttle 100, while the other branch 101 communicates with the mixing passage at the metering section 88 thereof. The cover 97 is provided with a downwardly extending boss 102 which is located immediately above the boss 93 and in co-operation therewith provides a restricted passage 103 forming a metering section in the suction passage at the fuel inlet 92.

Desirably a sleeve 104 is placed in the portion of the suction passage beyond the restricted passage and is provided with a restricted opening 105 communicating with the branch 99 of the suction passage which leads to the outlet section beyond the throttle 100. The lower end of the sleeve 104 desirably extends through the wall of the casing 85 and seats in a recess in the filler 89, thereby holding the filler in place. The filler 89 desirably is provided with a transverse slot 106 which extends through a considerable arc of the upper wall of the filler 89 and the filler desirably is provided with a segmental boss 107 in front of the slot 106 forming a shield at the end of the suction passage which communicates with the air metering section.

It has been shown experimentally that a shield placed in this position increases the suction head in the restricted passage at the fuel inlet relatively to the suction head in the air metering section as the engine load increases beyond half load and consequently increases the amount relatively proportional of fuel delivered to the metering section during heavy loads as compared with the amount delivered during light loads, presumably for the reason that when two currents of air flow into each other substantially at right angles, and one of said currents is considerably larger in volume than the other, it will tend to cut off the propo-

tional flow from the smaller passage when the velocity increases unless a shield is used. The relative increase in fuel delivered to the air metering section during heavy loads as compared with the amount delivered during light loads may be further increased by using series orifices in the fuel inlet conduit. This is particularly true if orifices are used which have a chamfered inlet, because it is a well-demonstrated fact that the discharge coefficient of such orifices increases gradually and very substantially as the suction head increases.

In the embodiment of the invention shown in Figs. 7, 8 and 9 this is accomplished by providing the small orifice 91 at the bottom of the conduit 92 with a chamfered inlet and the fuel inlet 94 with a chamfered valve.

In the construction illustrated in Figs. 7, 8 and 9, it is also imperative to provide for maintaining the liquid level in the fuel reservoir slightly below the fuel inlet 94 with a degree of precision heretofore unattained during idle and light load operations.

In the particular construction illustrated substantially the same principle is employed as that illustrated in Figs. 1 to 4. Float sections 108 and 109 are symmetrically disposed relatively to the fuel inlet 94 and are connected respectively to the arms 110 and 111 of a yoke 112 pivotally mounted at its end upon a pin 113 in a hollow extension 114 of the wall 90 of the fuel reservoir. The extension 114 is provided with an upwardly extending boss 115 which is bored vertically to supply a fuel passage 116 leading to the reservoir. The upper portion of the wall of the bore is screw threaded to receive complementary screw threads of a valve cage 117 which desirably has an angular or hexagonal enlargement 118 at a distance from its upper end.

In the construction shown in Fig. 7 the cover 97 is provided with a V-shaped notch 119 adapted to fit adjacent faces of the hexagonal enlargement 118 of the valve cage, thereby providing means for locking the valve cage from rotation when it has been adjusted at a predetermined height. The upper end portion of the valve cage is provided with external screw threads 120 to receive a coupling 121 for the end of the supply pipe 122. A valve seat member 123 is interposed between the coupling 121 and the upper end of the valve cage 117 and comprises a head which rests upon the upper end of the cage and a downwardly extending cylindrical portion 124 which desirably is pressed into the upper end of the vertical cylindrical passage 125 of the valve cage.

The valve member has a vertical central bore 126, the lower end of the wall of which is tapered to form a conical seat complementary to the conical upper end of a regulating valve 127 which extends axially of

the passage 125 of the valve cage and of the bore 116. The lower end of the valve is provided with a reduced extension 128 which passes through a suitable aperture in the yoke 112 in proximity to the pivot 113 of said yoke. The shoulder 129 at the base of the reduced extension 128 of the valve desirably is slightly rounded. The pivot of the yoke 112 is slightly above the point of engagement of the lower end of the valve with the yoke when the regulating valve is normally closed.

By reason of the adjustability of the valve cage 117 within the boss 115, the vertical position of the valve seat may be varied to establish the liquid level in the reservoir at a predetermined height slightly below the fuel inlet 94. In this construction the valve cage will be locked in adjusted position when the cover 97 of the reservoir is placed in position upon the top of the reservoir and secured thereupon by suitable screws.

The effective area of the fuel outlet is regulated by the valve 95 which desirably is of cylindrical form slidably mounted in a bearing in the boss 102 and extending across the metering section 103 of the suction passage into the fuel inlet 94. The lower end of the valve is chamfered on the down-stream side to present a flat face 130 extending at an acute angle to the axis of the valve. Preferably, but not necessarily, as illustrated in Fig. 7, a sleeve 131 is forced into the upper end of the inlet conduit 92 and the inner wall of the sleeve is complementary to the cylindrical up-stream wall of the valve 95. The effective area of the fuel outlet may be varied as required by vertical adjustment of the valve.

In the construction illustrated a spiral spring 132, which is seated upon the cover, surrounds the valve 95 and abuts at its upper end against a shoulder upon the under side of an enlarged portion 133 of the valve. A plate 134 is clamped upon the upper face of the enlarged portion of the valve by a nut 135. The plate 134 is engaged by the head of an adjusting screw 136 which is located in proximity to the valve 95 and in parallelism therewith and engages a screw threaded aperture in a boss 137 upon the cover. By reason of this construction a leverage is exerted by the spring 132 against the head of the adjusting screw 136 which maintains the cylindrical up-stream surface of the valve in constant engagement with the complementary wall of the inlet.

In the normal operation of the invention as above described, during the idle operation of the engine, with the throttle valve 100 in approximately closed position as illustrated in Fig. 7, the suction of the engine produces a partial vacuum in the branch 99 of the suction passage, thereby causing air to flow through the metering section 103 of the suc-

tion passage, thereby inducing the flow of fuel through the inlet 94 which mixes with the air in the suction passage and passes through the restricted aperture 105 and branch 99 to the engine. During such idle operation air is also caused to flow upwardly through the slot 106 in the filler 89 into the lower end of the branch 101 of the suction passage and out through the restricted aperture 105 to mingle with the fuel-air mixture drawn through the suction passage.

The area of the restricted passage 105 in the sleeve 104 is so proportioned relative to the area of the lower end of the branch 101 leading to the air metering section 88 in the mixing passage, and to the area of the metering section 103 of the suction passage, that the suction produced in the metering section 103 will maintain a flow of fuel from the fuel inlet at a low flowing head sufficient to produce satisfactory operation on idle.

It is well known that when air is drawn through an orifice of restricted area, such as the aperture 105, a maximum flow through that orifice will be induced when the pressure in the passage 99 is reduced to approximately fifty-three per cent of the barometric pressure. However, when fuel is entrained in the air drawn through such orifice, this limiting flow will be reached at a somewhat lower absolute pressure in the passage 99, but in any case the flow through the orifice 105 will be constant during a considerable period of operation as the throttle valve is gradually opened from idle. By reason of this fact a low flowing head is continuously maintained at the fuel inlet irrespective of the suction head in the metering section of the mixing passage 88 during idle and light load operation up to about half load.

The flow of air through the slot 106 from the metering section of the mixing passage toward the aperture 105 will be gradually reduced as the throttle valve is opened and a positive downward flow of fuel-air mixture will be induced through the slot 106 and into the metering section 88 of the mixing passage.

As the suction head in the metering section 88 increases a gradual lessening of flow toward the restricted opening 105 is produced, then a gradually increasing positive flow downwardly through the slot 106 is produced which builds up gradually from idle an increased suction at the metering section of the suction passage, thus inducing a greater flow of fuel from the fuel inlet 94. By reason of this construction the mixture flow is continuous and uninterrupted from the metering section of the suction passage and therebeyond.

One of the principal objects of the present invention is to provide means for delivering fuel through the fuel inlet continuously at a low, predetermined rate irrespective of the suction head in the metering section,

with unit-controlling means operable to change the ratio of fuel to air supplied to the mixing passage in conjunction with a mechanism arranged to maintain uninterrupted mixture flow from beyond said fuel inlet.

Unit control is accomplished by regulating the amount of fuel delivered through the fuel inlet. In the embodiment of the invention illustrated in Figs. 1 to 4 inclusive the area of the fuel inlet is regulated. In the embodiment of the invention disclosed in Figs. 7, 8, and 9, the suction head acting at the fuel inlet is regulated. In the particular construction shown in Fig. 7 this is accomplished by providing a choke valve or valves for controlling the admission of air into the inlet section of the metering passage. Obviously, when the choke valve or valves are in partially closed position the suction in the inlet section is much greater than when the choke valve is more widely open and the suction head applied to the inlet section will increase proportionately both the suction head at the metering section 88 and at the metering section 103 of the suction passage.

In the embodiment of the invention illustrated in Fig. 7 means are provided for supplying both hot and cold air to the carburetor with thermostatically controlled valves operable to vary the suction head in the inlet section during the warming up of the engine until normal operating temperatures are obtained and thereafter operable to vary gradually the relative proportions of hot and cold air to maintain the air admitted to the mixing passage at a proper temperature.

This may be readily accomplished by connecting to the fuel inlet section a thermostatic control for carburetors of the type disclosed in my prior Patent No. 1,627,947 granted May 10, 1927. This carburetor control comprises a tubular T-shaped casing 138, one of the branches 139 of which is telescopically mounted in and secured to the inlet end of the inlet section 86, with the other branch 140 forming the cold air inlet extending in the opposite direction. The hot air branch 141 extends at right angles to the branches 139 and 140. The means for choking the hot air inlet preferably comprises a thermostatically operable valve 142 of the character described in the patent aforesaid which, upon cold starting, is located approximately in the choking position illustrated, and as the engine warms up gradually rotates in a clockwise direction toward open position and as the hot air from the engine increases beyond a predetermined amount rotates beyond vertical position and acts gradually again to choke the admission of hot air.

The thermostatically operable valve 142 has connected to it an arm 143 which is con-

5 nected by a link 144 to the arm 145 connected to the shaft 146 of the choke valve 147 of the cold air inlet. The arrangement of the arms 143, 145, and link 144 is such that the initial opening movement of the thermo-
10 statically controlled choke valve 142, during cold starting and warming up of the engine, has but little effect upon the opening of the cold air valve 147, but as the thermo-
15 statically operable choke valve moves through and beyond vertical position the cold air valve 147 is moved toward open position with relatively increasing rapidity.

15 Desirably the shaft 148 of the thermostatic valve is extended through the wall of the branch 141 and is provided with an arm 149 the end of which is connected to a rod 150 leading to the instrument board, thereby providing manual means for rotating the thermostatic choke valve further toward closed 20 position than that which it normally assumes under the action of the thermostat.

25 In the operation of the device illustrated in Fig. 7, the operator may move the thermostatic choke valve of the hot air inlet to such choking position as to produce a suction head upon the fuel inlet sufficiently to supply the desired increased amount of fuel for cold starting. Such manual choking mechanism 30 may be immediately released upon the starting of the engine. Thereafter the proper suction head will be maintained by the action of the thermostat during the warming-up period of the engine, and also during changes in atmospheric temperature.

35 By reason of this construction, as well as that illustrated in Figs. 1 to 4, a carburetor for an internal combustion engine is provided comprising a mixing passage having a metering section, means for controlling the flow 40 through the mixing passage, a fuel inlet communicating with said metering section and subject to a suction head substantially proportional to the suction head at the metering section, with means for delivering fuel 45 through said inlet continuously at a low, pre-determined rate during idle and light load operation of the engine to supplement the rate of flow induced by the suction head in the 50 metering section, said fuel inlet and said controlling means being positioned relative to each other and co-ordinated with said mixing passage in such a manner as to provide uninterrupted mixture flow from said fuel inlet and therebeyond in combination with regulating means acting on a single fuel inlet to change the ratio of fuel to air supplied to the mixing passage. The advantage of 55 the present invention, which employs a low flowing head as compared with carburetor constructions in which the fuel is subject to a suction head at all times, is graphically shown in Fig. 10 in which ordinates represent fuel-air ratio, and the abscissas

represent loads from idle to full load. These curves are plotted from mathematical computations based upon the fundamental flow laws applying to fluids. From these curves it will be seen that below about $\frac{1}{3}$ load they diverge rapidly, thus representing a low flowing head of $\frac{1}{4}$ to $\frac{1}{2}$ " curving gradually with increasing slope downwardly indicating an increase in the richness of the mixture as idle load is approached which is 70 precisely what is desired, while the curves representing an initial suction head of $\frac{1}{4}$ to $\frac{1}{2}$ " rise rapidly indicating a leaning down of the mixture and soon reach a point where the mixture is so lean that engine operation is 75 impossible without supplementary mechanism to supply the defect.

80 Actual tests on a carburetor constructed in accordance with the invention disclosed herein show that a flowing head of $\frac{1}{4}$ " or slightly less gives excellent operation and 85 excellent economy, indicating that the curves here computed from the fundamental flow laws are closely approximated.

85 Fig. 11 is a graphic illustration plotted in a similar manner with curves in broken lines showing the mixture requirements necessary to give maximum power and maximum efficiency with a solid line superposed indicating the relative fuel-air ratio distribution 90 throughout the range of load of a carburetor constructed in accordance with the present invention.

95 It will be observed that the curve showing the mixture ratio produced by the simple arrangement of parts in the present invention with changes in throttle position approximates both the maximum efficiency curve in the range where efficiency is desired and meets the maximum power curve at wideopen 100 throttle where maximum power is desired.

105 It will be understood that the particular embodiments of the invention shown and described herein are of an illustrative character and are not restrictive of the meaning 110 and scope of the following claims.

Having thus described the invention, what is claimed as new, and desired to be secured by Letters Patent, is:

115 1. A carburetor for an internal combustion engine comprising a mixing passage having a metering section, means for controlling the flow through the mixing passage, a fuel inlet communicating with said metering section and subject to a suction head substantially proportional to the suction head at said metering section, means to maintain continuously a low flowing head 120 at said fuel inlet during idle and light load operation of the engine to supplement the rate of flow induced by the suction head in the metering section, said fuel inlet and said controlling means being positioned relative 125 ly to each other and co-ordinated with said 130

mixing passage in such manner as to produce uninterrupted mixture flow from said fuel inlet and therebeyond, in combination with regulating means responsive to variations in temperature acting upon said fuel inlet to change the ratio of fuel and air supplied to said mixing passage.

2. A carburetor for an internal combustion engine comprising a mixing passage having a metering section, means for controlling the flow through the mixing passage, a fuel inlet communicating with said metering section and subject to a suction head substantially proportional to the suction head at said metering section, means to maintain continuously a low flowing head at said fuel inlet during idle and light load operation of the engine to supplement the rate of flow induced by the suction head in the metering section, said fuel inlet and said controlling means being positioned relatively to each other and co-ordinated with said mixing passage in such manner as to produce uninterrupted mixture flow from said fuel inlet and therebeyond, in combination with regulating means respectively responsive to variations in temperature and barometric pressure acting on said fuel inlet to change the ratio of fuel and air supplied to said mixing passage.

3. A carburetor for an internal combustion engine comprising a mixing passage having a metering section, means for controlling the flow through the mixing passage, a fuel inlet communicating with said metering section and subject to a suction head substantially proportional to the suction head at said metering section, means to maintain continuously a low flowing head at said fuel inlet during idle and light load operation of the engine to supplement the rate of flow induced by the suction head in the metering section, said fuel inlet and said controlling means being positioned relatively to each other and co-ordinated with said mixing passage in such manner as to produce uninterrupted mixture flow from said fuel inlet and therebeyond, in combination with regulating means comprising a valve for said fuel inlet, thermostatic means within said passage engaging said valve, and pressure operable means outside of said passage acting to position said thermostatic means, and thereby change the ratio of fuel and air supplied to said mixing passage.

4. A carburetor for an internal combustion engine comprising a mixing passage having an undivided section of its length extending downwardly, a throttle valve in said mixing passage adapted to regulate the flow of mixture therethrough, and when at its idling position having its lower portion in proximity to a portion of the wall of said undivided section, a fuel inlet passage communicating with said undivided section of

said mixing passage in front of and above the lower portion of said throttle valve, said fuel inlet passage having means to restrict a portion of its cross sectional area to form a fuel metering passage remaining constant in area irrespective of changes in load on the engine and through which all the fuel delivered to said mixing passage shall pass during idle and light load operations of the engine, in combination with means to maintain continuously a low flowing head at said fuel metering section during idle and light load operations of the engine to supplement the suction head induced by the suction existing at the discharge end of said fuel inlet passage.

5. A carburetor for an internal combustion engine comprising a mixing passage having an undivided section of its length extending downwardly, a throttle valve in said mixing passage adapted to regulate the flow of mixture therethrough, and when at its idling position having its lower portion in proximity to a portion of the wall of said undivided section, a fuel inlet passage communicating with said undivided section of said mixing passage in front of and above the lower portion of said throttle valve, a fuel regulating valve in said fuel inlet passage adapted to remain in any desired adjusted position irrespective of changes in load on the engine and to control the effective area of said inlet passage through which all the fuel delivered to the mixing passage shall pass during idle and light load operations of the engine, in combination with means to maintain continuously a low flowing head at said fuel regulating valve during idle and light load operations of the engine to supplement the suction head induced by the suction existing at the discharge end of said fuel inlet passage.

6. A carburetor for an internal combustion engine comprising a mixing passage having an undivided section of its length extending downwardly, a throttle valve in said mixing passage adapted to regulate the flow of mixture therethrough, and when at its idling position having its lower portion in proximity to a portion of the wall of said undivided section, a fuel inlet passage communicating with said undivided section of said mixing passage in front of and above the lower portion of said throttle valve, said fuel inlet passage having means to restrict a portion of its cross sectional area to form a fuel metering passage remaining constant in area irrespective of changes in load on the engine and through which all the fuel delivered to said mixing passage shall pass during idle and light load operations of the engine, in combination with regulating means responsive to variations in temperature acting to change the quantity of fuel flowing through said fuel metering section relatively to the

quantity of air flowing through said mixing passage.

7. A carburetor for an internal combustion engine comprising a mixing passage having a metering section, a fuel inlet communicating therewith and subject to a suction head substantially proportional to the suction head at said metering section, means for delivering fuel through said fuel inlet continuously during idle and light load operations of the engine at a low predetermined rate to supplement the rate of flow induced by the suction head in said metering section, unit-controlling means comprising a valve for said inlet, a pivotally supported thermostatic device engaging said valve acting in response to increase in temperature to move the valve toward closed position, manual means operable to open the valve temporarily, and means operable to maintain uninterrupted mixture flow from said metering section and therebeyond during idle and light load operation as well as under heavy load.

8. A carburetor for an internal combustion engine comprising a mixing passage having a metering section, a fuel inlet communicating therewith subject to a suction head substantially proportional to the suction head at said metering section, means for delivering fuel through said fuel inlet continuously during idle and light load operation of the engine at a low predetermined rate to supplement the rate of flow induced by the suction head in said metering section, unit-controlling means comprising a valve for said fuel inlet, an elastic thermostatic element formed as a return bend having the end of one arm engaging said valve, a pivotal support for said thermostatic element, adjustable means initially to position said thermostatic element engaging the other arm thereof intermediate of said pivot and said valve, elastic means exerting a tension on said valve in opposition to said thermostatic device, and means operable to maintain uninterrupted mixture flow from said fuel inlet and therebeyond.

9. A carburetor for an internal combustion engine comprising a mixing passage having a metering section, a fuel inlet communicating therewith subject to a suction head substantially proportional to the suction head at said metering section, means for delivering fuel through said fuel inlet continuously during idle and light load operation of the engine at a low predetermined rate to supplement the rate of flow induced by the suction head in said metering section, unit-controlling means comprising a valve slidable in said fuel inlet, an elastic thermostatic element having two substantially right angle bends forming a return bend and having the end of one arm engaging said valve, a swinging pivot for said thermostatic element acting to maintain one side of said

valve in contact with a portion of the wall of said inlet, adjustable means initially to position said thermostatic element engaging the other arm intermediate of said pivot and said valve, manual means operable to open said valve temporarily against the resistance of said thermostatic element, and means operable to maintain uninterrupted mixture flow from said fuel inlet and therebeyond.

10. A carburetor for an internal combustion engine comprising a mixing passage having a metering section, a fuel inlet communicating therewith and subject to a suction head substantially proportional to the suction head at said metering section, a valve slidably mounted in said inlet having a wall complementary to a portion of the wall of said inlet port, and means for maintaining the same in contact therewith, said valve being chamfered on the opposite side, means for delivering fuel through said fuel inlet during idle and light load operation of the engine at a low, substantially constant, predetermined flowing head, to supplement the rate of flow induced by the suction head in said metering section, and means operable to maintain uninterrupted mixture flow from said metering section and therebeyond during idle and light load operation of the engine as well as under heavy load.

11. A carburetor for an internal combustion engine comprising a mixing passage having a metering section, a fuel inlet communicating therewith and subject to a suction head substantially proportional to the suction head in said metering section, a valve slidably mounted in said inlet having a wall complementary to the up-stream wall of said inlet port, said valve being chamfered on the opposite side, a thermo-sensitive device having means acting to maintain said complementary walls in contact and operable to force said valve into said inlet, and elastic means exerting a tension on said valve in opposition to said thermostatic device, means for delivering fuel through said fuel inlet during idle and light load operation of the engine at a low, substantially constant, predetermined flowing head to supplement the rate of flow induced by the suction head in said metering section, and means operable to maintain uninterrupted mixture flow from said metering section and therebeyond during idle and light load operation of the engine as well as under heavy load.

12. A carburetor for an internal combustion engine comprising a mixing passage having an air metering section of substantially constant area during idle and light load operation of the engine, a fuel inlet communicating with the mixing passage and subject to a suction head substantially proportional to the suction head at said metering section, means for delivering fuel through said fuel inlet during idle and light load

operation of the engine at a low predetermined rate to supplement the rate of flow induced by the suction head in said metering section, and means located beyond and in proximity to said fuel inlet operable to maintain uninterrupted mixture flow beyond said fuel inlet.

13. A carburetor for an internal combustion engine comprising a mixing passage having a metering section, a throttling valve with its lower end portion below and beyond said metering section, a fuel inlet positioned above the lower portion of said metering section and subject to a suction head substantially proportional to the suction head in said metering section, and means to maintain continuously a low substantially constant flowing head at said fuel inlet during idle and light load operation of the engine to supplement the rate of flow induced by the suction head in said metering section.

14. A carburetor for an internal combustion engine comprising a mixing passage having a metering section, a throttling valve with its lower end portion below and beyond said metering section, a fuel inlet positioned above the lower portion of said metering section and subject to a suction head substantially proportional to the suction head in said metering section, a fuel reservoir surrounding said fuel inlet, a passage leading upwardly therefrom to said fuel inlet, and means for maintaining continuously during normal operation of the engine the liquid level in said reservoir at a height slightly above said fuel inlet.

15. A carburetor for an internal combustion engine comprising a mixing passage having a metering section, a throttling valve with its lower end portion below and beyond said metering section, a fuel inlet positioned above the lower portion of said metering section and subject to a suction head substantially proportional to the suction head in said metering section, a fuel reservoir surrounding said fuel inlet and communicating therewith, means for supplying fuel to said reservoir including a regulating valve, float sections in said reservoir symmetrically positioned relatively to said fuel inlet, lever mechanism intermediate of said float sections and said valve operable to transmit a sufficiently large and substantially constant multiplied force to said regulating valve regardless of the inclination of said reservoir and thereby to maintain the liquid level in the reservoir, with only small variations in height, slightly above said fuel inlet during idle and light load operations of the engine.

16. A carburetor for an internal combustion engine comprising a mixing passage having a metering section, a throttling valve with its lower end portion below and beyond said metering section, a fuel inlet positioned

above the lower portion of said metering section and subject to a suction head substantially proportional to the suction head in said metering section, and means to maintain continuously a low predetermined flowing head at said fuel inlet to supplement the rate of flow induced by the suction head in said metering section during normal operation from idle to about half load position of said throttling valve.

17. A carburetor for an internal combustion engine comprising a mixing passage having a metering section, a throttling valve with its lower end portion below and beyond said metering section, a fuel inlet positioned above the lower portion of said metering section and subject to a suction head substantially proportional to the suction head in said metering section, and means to maintain continuously a low predetermined flowing head at said fuel inlet to supplement the rate of flow induced by the suction head in said metering section during normal operation from approximately closed to half open position of said throttling valve, said throttling valve being arranged to reduce the effective area of said metering section when moved from beyond half open position toward full open position.

18. A carburetor for an internal combustion engine having a mixing passage provided with a depression intermediate of its length, a fuel inlet communicating with said passage in front of and above the lower portion of said depression, a fuel reservoir surrounding said fuel inlet and communicating therewith, and means for maintaining, continuously, the liquid level in said reservoir at a height slightly above said fuel inlet during idle and light load operations of the engine, and means for throttling said passage at said depression and below the level of said fuel inlet.

19. A carburetor for an internal combustion engine comprising a mixing passage having relatively inclined inlet and outlet sections forming at their junction a depression, a fuel inlet communicating with said inlet section above the lower portion of said depression, and means for throttling said passage beyond and below the level of said fuel inlet approximately at the junction of the outlet and inlet sections.

20. A carburetor for an internal combustion engine having a mixing passage provided with a depression intermediate of its length and having a restricted portion which remains constant in area during idle and light load operations of the engine located in front of said depression, a fuel inlet communicating with said restricted portion, and a throttling valve in said passage with the lower portion thereof located beyond and below said fuel inlet and so shaped and po-

sitioned that when approaching wide open position it will reduce the effective area of said restricted portion.

21. A carburetor for an internal combustion engine having a mixing passage provided with a depression intermediate of its length and having a restricted portion which remains constant in area during idle and light load operations of the engine located in front of and adjacent to said depression, a fuel inlet communicating with said restricted portion, and a swinging throttle valve extending into said depression operable, when approaching full open position, to reduce the effective area of said restricted portion.

22. A carburetor for an internal combustion engine comprising a mixing passage having relatively inclined inlet and outlet sections forming at their junction a depression, said inlet section having a restricted portion which remains constant in area during idle and light load operations of the engine located in front of and adjacent to said depression, a fuel inlet communicating with said restricted portion, a fuel reservoir therefor surrounding said fuel inlet and said depression, a regulating valve slidable in said fuel inlet having a wall complementary to the wall of said inlet and chamfered on the opposite side, thermostatic means in said passage controlling said regulating valve having means operable to maintain continuous light engagement between said complementary walls, without restraining the action of the thermostatic means, and a throttling valve extending into said depression during idle and light load operations of the engine.

23. A carburetor for an internal combustion engine comprising a mixing passage having relatively inclined inlet and outlet sections forming at their junction a depression, said inlet section having a restricted portion which remains constant in area during idle and light load operations of the engine located in front of and adjacent to said depression, a fuel inlet communicating with said restricted portion, a swinging throttle valve extending into said depression, during idle and light load operations of the engine, a reservoir surrounding said fuel inlet and communicating therewith, means to maintain the liquid level in said reservoir slightly above said fuel inlet, controlling means comprising a valve for said inlet, thermostatic means within said mixing passage engaging said valve, and means initially to position said thermostatic means.

24. A carburetor for an internal combustion engine comprising a mixing passage having relatively inclined inlet and outlet sections forming at their junction a depression, said inlet section having a restricted portion which remains constant in area during idle and light load operations of the engine lo-

cated in front of and adjacent to said depression, a fuel inlet communicating with said restricted portion, a swinging throttle valve extending into said depression, during idle and light load operations of the engine, a reservoir surrounding said fuel inlet and communicating therewith, means to maintain the liquid level in said reservoir slightly above said fuel inlet, during idle and light load operations of the engine, controlling means comprising a valve for said inlet, thermostatic means within said passage engaging said valve, and pressure-operable means acting to position said thermostatic means.

25. A carburetor for an internal combustion engine comprising a mixing passage having relatively inclined inlet and outlet sections forming at their junction a depression, said inlet section having a restricted portion which remains constant in area during idle and light load operations of the engine located in front of and adjacent to said depression, a fuel inlet communicating with said restricted portion, a swinging throttle valve extending into said depression, during idle and light load operations of the engine, a reservoir surrounding said fuel inlet and communicating therewith, means to maintain the liquid level in said reservoir slightly above said fuel inlet, during idle and light load operations of the engine, controlling means comprising a valve for said inlet, a pivotally supported thermostatic device engaging said valve acting, in response to increase in temperature, to move the valve toward closed position, and elastic means tending to move the valve toward open position against the resistance of said thermostatic device.

26. A carburetor for an internal combustion engine comprising a mixing passage having relatively inclined inlet and outlet sections forming at their junction a depression, said inlet section having a restricted portion which remains constant in area during idle and light load operations of the engine located in front of and adjacent to said depression, a fuel inlet communicating with said restricted portion, a swinging throttle valve extending into said depression, during idle and light load operations of the engine, a reservoir surrounding said fuel inlet and communicating therewith, means to maintain the liquid level in said reservoir slightly above said fuel inlet, during idle and light load operations of the engine, controlling means comprising a valve slidable in said inlet, an elastic thermostatic element having two substantially right angle bends forming a return bend and having the end of one arm engaging said valve, a strut pivotally mounted at one end and inclined away from the axis of the valve engaging said element at one of said right angle bends, and adjustable means initially to position said thermostatic element engaging the other arm inter-

mediate of the engaged bend and said valve,
and manual means operable to open said valve
against the resistance of said thermostatic
element.

⁵ In testimony whereof, I have signed my
name to this specification.

MERL R. WOLFARD.
